(57) **CLAIM**

The ornamental design for a curtain mounting frame, as shown and described.

DESCRIPTION

FIG. 1 is a front, top perspective view of a curtain mounting frame, showing our new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top view thereof;

FIG. 8 is an enlarged bottom view thereof;

FIG. 9 is an enlarged view of detail "9" identified in FIG. 1;

FIG. 10 is an enlarged view of detail "10" identified in FIG. 1; and,

FIG. 11 is an enlarged view of detail "11" identified in FIG. 2.

The dashed lines in the figures illustrate portions of the curtain mounting frame that form no part of the claimed design. The dash dot dash lines in FIGS. 1, 2, 9, 10 and 11 are for the purpose of illustrating the enlarged view indicators and form no part of the claimed design.
